(57) **CLAIM**

I claim the ornamental design for an automotive vehicle wheel, as shown and described.

DESCRIPTION

FIG. 1 is a top perspective view showing an automotive vehicle wheel of my new design;
FIG. 2 is a side plan view thereof;
FIG. 3 is a top plan view thereof;
FIG. 4 is a rear plan view thereof;
FIG. 5 is a bottom plan view thereof;
FIG. 6 is a front plan view thereof; and,
FIG. 7 is a side plan view thereof, opposite FIG. 2.
The broken lines (for example the back side of the wheel) illustrate portions of the automotive vehicle wheel that form no part of the claimed design. The stippling indicates a contrast in appearance.
